CLAIM

USPC **D24/129**

The ornamental design for a blood flow chamber with directional arrow, as shown and described.

(58) **Field of Classification Search**

DESCRIPTION

USPC D24/129, 169; D10/81
CPC A61B 5/1455; A61B 5/14557; A61M
2205/3306; A61M 2230/30

FIG. 1 is a perspective view of a blood flow chamber with directional arrow showing our new design;

See application file for complete search history.

FIG. 2 is a top plan view of the blood flow chamber with directional arrow of FIG. 1;

FIG. 3 is a bottom plan view of the blood flow chamber with directional arrow of FIG. 1;

FIG. 4 is a side elevation view of the blood flow chamber with directional arrow of FIG. 1;

FIG. 5 is one end elevation view of the blood flow chamber with directional arrow of FIG. 1; and,

FIG. 6 is another end elevation view of the blood flow chamber with directional arrow of FIG. 1.

Features illustrated in broken lines in the Figures form no part of the claimed design, and broken lines immediately adjacent the shaded areas represent the bounds of the claimed design.
